SURGEON'S SCRUB SINK

Robert W. Nagel, Floyds Knobs, Ind., assignor to American Standard Inc., New York, N.Y., a corporation of Delaware

Filed July 26, 1968, Ser. No. 12,922

Term of patent 14 years

Int. Cl. D23—02

U.S. Cl. D23—58

Fig. 1.

Fig. 3.

Fig. 4.

Fig. 2.

FIGURE 1 is a perspective front view of my surgeon's scrub sink embodying the new design;

FIGURE 2 is a front elevational view thereof;

FIGURE 3 is a top plan view thereof; and

FIGURE 4 is a side elevational view thereof.

The broken line representation of a stream of water in FIGURE 1 is for purposes of illustration only.

I claim:

The ornamental design for a surgeon's scrub sink, substantially as shown and described.
